UNITED STATES PATENT OFFICE.

GEORGE P. MACREADY AND JAMES R. BOWIE, OF PROVIDENCE, RHODE ISLAND, ASSIGNEES TO FRANKLIN MACHINE COMPANY, OF PROVIDENCE, RHODE ISLAND, A CORPORATION OF RHODE ISLAND.

PNEUMATIC DROP HAMMER.

Application filed August 13, 1921. Serial No. 491,900.

To all whom it may concern:

Be it known that we, GEORGE P. MACREADY and JAMES R. BOWIE, citizens of the United States, and residents of

5 Providence, in the county of Providence and State of Rhode Island, have invented certain new and useful Improvements in Pneumatic Drop Hammers, of which the following is a specification.

10 This invention relates to pneumatic drop hammers, and more particularly to such drop hammers used in precision work such as jewelers' work and the like.

Broadly stated, it is an object of the 15 present invention to provide an improved form of drop hammer, in which rebound of the ram shall be effectively prevented, so that accurate precision work may be reliably produced.

20 More particularly, it is one object to provide a drop hammer automatically or manually operable, employing a compressed medium such as air as the actuating agent, and which is controlled by an improved 25 form of control mechanism.

Another feature relates to an improved adjustable exhaust valve, whereby the time lag of the ram may be predetermined.

Still another feature relates to employing 30 the actuating medium for definitely seating the control valve, whereby leakage is effectively prevented, despite wear of the parts.

Another feature relates to sending an 35 impulse of the actuating medium through the exhaust valve thus preparing it for use in exhausting the cylinder and assuring correct operation thereof.

Other objects will appear as the description 40 of the invention progresses.

Like reference characters designate like parts in the several figures.

Referring to the drawings,

Figure 1 shows a front elevation of the 45 press;

Figure 2 shows a plan view of a portion of the top of the mechanism with parts broken away;

Figure 3 shows a section taken on the 50 lines 3—3 of Figure 2 with parts broken away;

Figure 4 shows a section on the lines 4—4 of Figure 2;

Figure 5 shows a section on the lines 5—5 of Figure 3;

Figure 6 shows a plan view of the exhaust valve;

Figure 7 shows a sectional elevation taken on the lines 7—7 of Figure 6.

10 designates a metal frame preferably 60 of iron or steel adapted to be bolted to a piston or a work table 11 by means of bolts 12. Said frame has laterally extending webs 13 to impart strength and rigidity to the structure. The inwardly facing faces 65 14 and 15 of the frame 10 are substantially parallel and in spaced relation with each other and the surfaces thereof are ground or machined to insure a smooth and even surface. 70

The upper portions of the frames 10 are secured together by a cross member 16 suitably attached thereto by a plurality of bolts 17.

Slidably mounted along the smooth surfaces 14 and 15 is a ram 20 preferably formed of metal and having a relatively large mass. Said ram 20 is secured to a plunger rod 21 by means of a clamp 22. Slidably mounted on the plunger 21 is an 80 adjustable stop 23, whose position may be changed at will by means of a machine screw 24. Resting upon the upper face of the stop 23 is a spring 25 comprising a few coils for taking up the shock, as will be presently set forth. 26 is a trigger attached to the ram and extending from the side thereof for a purpose which will be subsequently described. To the lower surface of ram 20 may be secured in any well known manner a die press member (not shown) 90 cooperating with a stationary die press member on the frame or bench. 85

The plunger 21 rides through a stuffing box 32 in the cross piece 16 as shown in 95 Figure 3 and into a cylinder 30 preferably made of brass or other suitable metal mounted on the upper surface of the cross piece 16. The upper end of plunger 21 is secured to the piston 31 in any suitable 100 manner; the piston 31 being tightly fitted within the cylinder 30 and being preferably

made of a plurality of layers to secure a tight fit. The stuffing box 32 is provided with a retaining nut 33 adapted to cooperate with a spanner wrench for tightening the plunger. The upper part 34 of the cylinder 30 may be left open to the atmosphere.

Mounted in a bearing such as 40 along one of the vertical supporting frame members 10 is an axially movable rod 41. Pivotally secured to the upper end of this rod is a bell crank lever 42. A pivot 43 mounted on the frame supports said lever. Pivotally secured to the other end of the bell crank lever 42 is a horizontal rod 44, whose free end is adapted to push against a bell crank lever 45 which is suitably mounted in a horizontal plane on the pivot 46 as shown in Figure 2. Vertical movement of the rod 41 caused by the operation of handle 49 results in a horizontal movement of rod 44 and displacement of bell crank lever 45. The end 48 of the bell crank lever 45 intercepts the valve shaft 72 for a purpose which will be more fully described later. The bell crank lever 45 is provided with a retractile spring 47 suitably secured to the pin in the cross-piece 16.

On the frame member 10 opposite that to which rod 41 is secured is a vertical operating rod 50 axially movable in the trunnion 51 of the base and bearing 52 of the cross piece 16 (see Figure 3). The upper extremity of rod 50 extends within a dash pot cylinder 54 and is provided with a tight fitting piston 53. An aperture 55 in an intermediate portion of the said wall of the cylinder 54 permits sluggish movement of the piston 53 in its respective positions. The operating rod 50 is adapted to be retained in a given position by means shown in Figure 4 comprising a spring pressed ball 60 riding in a cylindrical well in the cross piece 16. Two lunar shaped notches in the rod 50 receive the ball 60 in the predetermined position. An adjustment for the spring is provided by means of a set screw 62 and a suitable lock nut.

A stop member 65 is provided with a handle for conveniently operating the rod 50 when the machine is to be operated manually. Said stop 65 is secured to the rod 50 in any suitable manner, as, for example, by set screw or lock nuts. The adjustable stop 66 is slidably mounted on the rod 50 above the ram 20 and may be set in any desired position by means of a set screw shown in Figure 1. By this means the automatic operation of the mechanism is controlled. 67 is a safety stop suitably secured to the rod 50 for preventing extreme operation of the ram 20 in case of failure of stop 66 to be tightly secured or in case the operator inadvertently permits extreme movement.

Slidably mounted on the rod 50 is a brack-

et 70 having a laterally extending portion terminating in bifurcated ends 71. These ends engage between collars 73 and 77 secured to a valve shaft 72 so that movement of the rod 50 also causes axial movement of the valve shaft 72. A pair of collars 74, 74 is provided, one on either side of the bracket 70, suitably secured to the shaft 50 by means of pins or the like. The compression springs 75 support the bracket 70 intermediate these collars and are adapted to prevent damage to collars 77 and 78 and other parts of the mechanism if the rod 50 is moved too far. Valve shaft 72 is tightly fitted within a chamber in the valve frame 76, said valve frame being integral with the cross piece 16. The collar 77 by contacting with the lower face of the frame 76 limits the upward movement of valve shaft 72 and similarly a collar 78 suitably secured to the valve shaft 72 by means of a pin 79 limits the downward movement thereof.

An axial hole 80 is drilled for a portion of the length of the shaft, its outer end being sealed by a plug 81 or other suitable means. A groove or channel 82 parallel to the hole 80 is cut in the periphery of valve shaft 72 in such a position and of such length that when the fork 71 is in its extreme downward position, the inlet 83 is connected with the passage 84 leading to the cylinder 30.

The groove 82 is connected with the hole 80 by a passage 85. A passage 86 is provided in the frame 76 in such a position that groove 82 coacts therewith when the valve shaft 72 is in its extreme upper position. A second radial passage 87 in the valve shaft 72 is provided in such a position that the hole 80 is thereby connected with the passage 86 only when the valve shaft 72 is in an intermediate position and for only a relatively short portion of the movement of the valve shaft 72.

A passage 90 interconnected to the passage 86 with an exhaust valve 91 shown in detail in Figures 6 and 7. The exhaust valve 91 is provided with means for adjustably determining the rate of exhaust of compressed medium to the atmosphere so that the action of the weight 20 may be accurately varied. Said exhaust valve 91 comprises a frame or casing 92 forming a hollow chamber open at the top. This chamber is closed by a suitable face plate 93 secured by suitable flat-head screws to the casing 92 as shown in Figure 6. In intimate contact with the upper part of the face plate 93 there is provided a relatively flat sliding member 94 provided with an outwardly extending arm having bifurcations for a purpose which will be subsequently set forth. A second relatively flat slide member 95 is secured to the sliding member 94 by means of suitable

flat-head screws extending through perforations in the plate 93 and is held in intimate contact with the lower face of the plate 93. A spring 96 positioned within the casing 92 maintains the second sliding member 95 in intimate contact with the lower plate 93. Screw-threaded into a lug extending laterally through the casing 92, is a rod having a thumb nut 97 and a collar engaging the 5 forked extension on the slide 94 and by rotating the nut 97 the slide 94 and slide 95 may be adjusted in desirable position. The slides 93, 94 and 95 are provided with suitable perforations and in one position of the thumb 10 nut 97 these perforations match with each other thereby providing passage through the interior of the casing 92 to atmosphere, and in other positions are partially or completely closed. The spring 96 compresses the slide 15 95 against the plate 93 so as to effectively seal the casing against leaks when the valve is completely or nearly fully closed. The slides 94 and 95 may be locked in desirable 20 position by means of thumb nuts 98 the stems of which enter elongated slots in the slide 94.

A source of actuating agent such as compressed air is connected to the pipe 35 leading to the mechanism. Intermediate this 30 pipe is a valve 36. The pipe 35 is operatively connected to the passage 83 and also to the chamber 37 through a passage such as 201 (see Fig. 2). The chamber 37 is sealed by a suitable plug and is provided with a 35 drain channel closed by a drain plug 38. A portion 39 of valve shaft 72 as shown in Figure 5 is cut away and the pressure of the air against the substantially flat part of the valve shaft 72 thus presses the shaft against 40 the portion of the frame 76 which seals the passages 83, 84 and 86 and provides an effective seal against escape of the compressed air.

In operation it will first be assumed that 45 the apparatus is shut down. The ram 20 is in its extreme downward position resting upon a suitable die plate not shown. The valve shaft 72 is in the downward position as shown in Figure 3. The source of compressed air is now connected to the mechanism, the valve 36 being turned on. The 50 compressed air traverses the pipe 35, passages 83, 82 and 84 and enters the bottom portion of cylinder 30 thus raising the piston 31, plunger 21 and the ram 20. If the device is to be operated manually the operator permits the ram to be raised until the stop 23 is immediately below the cross-piece 16, whereupon the operator raises the handle 65, after having released the same by actuating handle 49 and thereby displacing bell crank lever 45. It will be noted that the compression spring 25 takes up the shock and that the adjustable stop 23 predetermines the height to which the ram is raised.

Manipulation of the handle 65 upwardly now raises the rod 50, bracket 70 and valve shaft 72 and during an intermediate portion of the travel the source of compressed air is connected by one of the passages 83, 82, 80, 70 87, 86, 90 to the exhaust valve and through it to the atmosphere, thus insuring proper operation of the exhaust valve before introducing an impulse of compressed air therethrough. Further movement of valve shaft 75 72 upwardly disconnects passage 83 from the groove 82 and connects the passage 84 by way of groove 82 to passages 86 and 90. Thus the lower portion of the cylinder 30 is connected to the atmosphere and escape of 80 the air permits the ram 20 to fall. The speed of the drop is predetermined by the adjustment of the exhaust valve slide 95. The contact of the ram 20 with the stationary press member accomplishes the desired 85 work of stamping out jewelry or the like. The trigger 26 is brought into contact with a portion of the member 65 and causes downward movement of the lever 50 and thus of the valve shaft 72 thereby automatically disconnecting the cylinder 30 from the atmosphere and again connecting it by one of the passages 84, 82 and 83 with the source of compressed air and automatically raising the piston. The ram is again raised until it 90 reaches the position determined by stops 23 and remains there until the bell crank lever 45 is again displaced by the operation of handle 49. The operation may now be repeated manually as many times as desired. It will be noted that only a single downward movement of the ram 20 is permitted and that as soon as the ram contacts with the work the actuating medium is again made effective for restoring the ram to its upper 105 position.

For automatically operating the ram the handle 49 is locked out of the way in any suitable manner. Thus the bell crank lever 45 has no control over the movement of valve shaft 72. The stop 66 is adjusted so that when the trigger 26 and the ram 20 reach a predetermined upper position the valve mechanism is automatically actuated instead of being actuated by hand. The ram thereupon drops and acts upon the work in the same manner as before, the operation being automatically repeated until the handle 49 is restored. The plate 93 is provided with a plurality of perforations such as 101 of 110 which 4 are shown by way of example. The slide 95 is provided with a similar number of perforations such as the perforations 102 positioned so that in one position of the slide 95 the perforations 102 are in alignment with the corresponding perforations 101. A flat head machine screw 103 extends from the slide 95 to member 94, and is movable therewith through a recess 104, cut in the plate 93 as clearly indicated in Figure 7. 115 120 125 130

The present disclosure is one form in which the invention may be practised, but numerous modifications may be made therein without departing from the spirit of the invention. We therefore do not wish to be limited by the present disclosure but instead by the scope of the appended claims.

What we claim is:

1. In a pneumatic drop hammer, a compressed air supply pipe, a control valve adapted to alternately admit and release compressed air comprising a perforated body member, an elongated shaft slidable in the perforation thereof, of substantially circular cross section through a portion of its length, the inlet and exhaust passages being disposed on one side of the intermediate portion of said shaft and adapted to cooperate with corresponding passages in the body member, a portion of the shaft diametrically opposite said shaft passages being cut away to form a chamber between it and the adjacent wall of the body member and a connection forming a communicating passage between said chamber and said air supply pipe, whereby the compressed air maintains said shaft against the portion of the body member having the inlet and exhaust passages, to seal said passages against leakages.
2. In a pneumatic drop hammer and control valve, a source of compressible medium connected to the inlet chamber of said valve for supplying medium to the hammer for raising the hammer, an exhaust chamber for the hammer control by said valve to cause said hammer to drop, said valve being formed with a recess having a conducting passage from said source of compressed medium to said recess for effectively setting said valve.
3. In a pneumatic drop hammer, a controlling valve therefor comprising a perforated body member, a reciprocating shaft slidable through the perforation, a pair of collars fixed to said shaft on one side of said member in spaced relation, an actuated rod substantially parallel to said shaft and in spaced relation therewith, a bracket resiliently supported on said rod having a bifurcated transverse arm partially enclosing said shaft at a point between said collars and a third collar fixed to said shaft on the other side of said member adapted to limit the extent of movement of said shaft, one of said first-named collars being adapted to limit the extent of a different movement of the shaft.
4. In a pneumatic drop hammer, a controlling valve therefor comprising a perforated body member, a reciprocating shaft slidable through the perforation, a pair of collars fixed to said shaft on either side of said member adapted to contact in different positions of the shaft with the respective faces of said member to limit the extent of

movement thereof, an actuating rod substantially parallel to said shaft and in spaced relation therewith, and resilient means operatively interconnecting said rod and said shaft.

5. In a pneumatic drop hammer, a controlling valve therefor comprising a shaft for opening and closing the valve parts, a reciprocating rod, a forked member loosely mounted on said rod and engaging said shaft and resilient means operatively interconnecting said rod and forked member.

6. In a die press, controlling means therefor, comprising a reciprocating shaft and a movable stop member to prevent the operation of said controlling means, said stop member comprising a bell crank lever, a retractile spring for maintaining one arm of said lever to intercept the path of movement of said reciprocating shaft, and a manually operated push rod to withdraw said lever from said path.

7. In a pneumatic drop hammer, a controlling valve therefor, a reciprocating rod adapted to operate said valve, and a locking mechanism for said rod comprising a depression in the periphery of the rod, a ball formed to enter the depression, resilient means for retaining said ball in the depression, and means for adjustably varying the tension of said spring.

8. In a drop hammer, the combination with a controlling valve for said hammer including a casing and including a member slidable in said casing in one direction, of means for supplying a compressible medium to the valve for lifting the hammer, said slidable member having a recess a conducting passage from said recess communicating with said source of supply whereby movement of the member in a relatively different direction is controlled by said medium.

9. In a drop hammer, the combination with a controlling valve for said hammer including a casing having ports, and including a member slidable in said casing in one direction, of means for supplying a compressible medium to the valve for lifting the hammer, said slidable member having passages communicating with said ports, at least one of said passages being positioned in the side of said member and a pipe connected to said passage and communicating with said source of supply whereby movement of the member in a relatively different direction is controlled by said medium.

10. In a drop hammer, the combination with a control valve for said hammer including a casing having ports, and including a member slidable in said casing in one direction, of means for supplying an expansible medium to the valve for lifting the hammer, said slidable member having passages communicating with said ports, and

having a recess in a side opposite said passages communicating with said source of supply to retain quality of the medium whereby the member is forced into intimate contact with the face of the casing having said parts therein.

11. In a drop hammer, a ram, a cylinder, a piston slideable within the cylinder and operatively connected with the ram, a valve 10 casing having ports in one face thereof communicating with said cylinder, a valve member slideable in one direction within said casing and having passages communicating with certain of said ports at different

periods of the movement of said member, 15 and a source of compressible medium for actuating said piston, said valve member having a recess in a side opposite said passages communicating with said source to retain a quantity of the medium whereby the member is forced into intimate contact with the face of the casing having said ports therein.

Signed at Providence in the county of Providence and State of Rhode Island, this eighth day of August, A. D. 1921.

GEO. P. MACREADY.
JAMES R. BOWIE.
